US0D1048423S

(12) **United States Design Patent** (10) Patent No.: **US D1,048,423 S**
(45) Date of Patent: ** Oct. 22, 2024

(54) **BUNION CORRECTOR**

(71) Applicant: **Zihuan Ye**, Shenzhen (CN)

(72) Inventor: **Zihuan Ye**, Shenzhen (CN)

(73) Assignee: **Zihuan Ye**, Shenzhen (CN)

(**) Term: **15 Years**

(21) Appl. No.: **29/874,912**

(22) Filed: **Apr. 26, 2023**

(30) **Foreign Application Priority Data**

Nov. 4, 2022 (CN) 202230734697.0

(51) **LOC (14) Cl.** **24-02**

(52) **U.S. Cl.**

USPC **D24/192**

(57) **CLAIM**

The ornamental design for a bunion corrector, as shown and described.

DESCRIPTION

FIG. 1 is a front perspective view of a bunion corrector, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the equal-length broken lines depict portions of the bunion corrector that form no part of the claimed design.

1 Claim, 7 Drawing Sheets
